(57) **CLAIM**

The ornamental design for a respirator mask, as shown and described.

DESCRIPTION

FIG. 1 is a front perspective view of a respirator mask, showing our new design;

FIG. 2 is a right side elevation view thereof;

FIG. 3 is a left side elevation view thereof;

FIG. 4 is a front elevation view thereof;

FIG. 5 is a bottom-up view thereof;

FIG. 6 is a top-down view thereof; and,

FIG. 7 is a back elevation view thereof.

The broken line portions showing the mask interior in FIG. 7 are shown to illustrate environment only and form no part of the claimed design.
